(57) **CLAIM**

The ornamental design for a storage container as shown and described.

DESCRIPTION

FIG. 1 is a perspective view of a storage container according to one embodiment, with a support bracket in a retracted position.

FIG. 2 is another perspective view of the storage container of FIG. 1.

FIG. 3 is a first plan view of the storage container of FIG. 1.

FIG. 4 is a second plan view of the storage container of FIG. 1.

FIG. 5 is a first side view of the storage container of FIG. 1.

FIG. 6 is a second side view of the storage container of FIG. 1.

FIG. 7 is a first end view of the storage container of FIG. 1.

FIG. 8 is a second end view of the storage container of FIG. 1.

FIG. 9 is a perspective view of the storage container of FIG. 1, with a support bracket in an extended position.

FIG. 10 is another perspective view of the storage container of FIG. 9.

FIG. 11 is a first plan view of the storage container of FIG. 9.

FIG. 12 is a second plan view of the storage container of FIG. 9.

FIG. 13 is a first side view of the storage container of FIG. 9.

FIG. 14 is a second side view of the storage container of FIG. 9.

FIG. 15 is a first end view of the storage container of FIG. 9; and,

FIG. 16 is a second end view of the storage container of FIG. 9.

Any portions shown in dash-dot lines form no part of the claimed design.

1 Claim, 16 Drawing Sheets
